UNITED STATES PATENT OFFICE

2,617,538

HANGER

Leonard Martin, Springfield, Mass.

Application September 13, 1950, Serial No. 184,559

3 Claims. (Cl. 211—123)

1

My invention relates to new and useful improvements in a hanger construction and is directed more particularly to the provision of a device of this general class which offers means for obtaining a multiplicity of positions or arrangements for hanging various items for drying purposes and to improvements in such means.

It is the principal object of my invention to provide a novel and improved construction of the type in which a plurality of positions or arrangements of the relative parts may be made, each of the same producing a unique result which contributes to the sum total of the novel features of my invention, and there is the further provision of a particular construction which will facilitate the drying of wet clothes over a bathtub, in the manner which is now well known and understood, and which will eliminate the present objectionable inconveniences in such a practice.

It is another object of my invention to provide a device which will operate with a maximum amount of ease and a minimum degree of effort.

One of the primary purposes of my invention is to provide structural and operational improvements in devices of the class to which reference has been made, which improvements not only simplify the structure as such, but also provide important distinct advantages in strength, durability, and the like.

With the above primary objects in view, it is another object of my invention to provide a construction of the above described character in which the number of operating parts is greatly reduced and which is compact in accordance with the demands and desires of manufacturers and purchasers alike and which is not only distinctive in its appearance and practical in its value but also reliable in its operation and efficient in its use.

It is a still further object to provide a device which is constructed of relatively simple component parts which are adapted to be readily assembled in a multiplicity of arrangements and which, when once assembled, are effectively held in operative relationship.

Other prime objects of my invention include: first, the securement of a higher degree of accuracy and greater degree of variety in the manner of work performed therewith than has heretofore been possible with prior devices known in the art; second, the attainment of a higher speed of construction and assembly of the device due to its simplification of design and its unique composition of parts; third, the attainment of flexibility and a capability of adjustment by which a

2

large variety of work can be produced by means of the same device; fourth, the provision of an improved hanger construction which may be made more economically and with fewer operations in the manufacture of its parts, as well as in the assembly thereof, than prior devices known in the art; fifth, the provision of a construction which may be readily installed with respect to the various purposes for which it is intended; and sixth, the provision of such other improvements in and relating to hangers of the above referred to type as are hereinafter described and claimed.

My invention also consists in certain new and original features of construction and combination of parts hereinafter set forth and claimed in conjunction with the annexed drawings which illustrate a certain form of embodiment thereof, which form is deemed preferable and is a specific disclosure for the purpose of illustrating one embodiment of the invention by way of an example since the same has been found in practice to give satisfactory and reliable results, although it is to be understood that the various parts of which the invention consists can be variously changed within the scope of the appended claims without departing from the broad aspects or spirit of the invention and that same is not limited to the precise arrangement and organization of the instrumentalities as herein shown and described.

All of the above cited objects I accomplish by means of such structure and relative arrangement of parts thereof, as will fully appear by a perusal of the description below and by various specific features which will hereinafter be set forth.

To these above and other ends and with the foregoing and various other features and advantages and other objects of my invention as will become more readily apparent as the description proceeds, my invention consists in certain novel features of construction and in the combination and arrangement of parts as will be hereinafter more particularly pointed out in the claims hereunto annexed and more fully described and referred to in connection with the accompanying drawings wherein:

Fig. 1 is a broken side elevational view of the device of my invention;

Fig. 1a is a partial front elevational view of the device shown in Fig. 5 showing a different arrangement of the rod members;

Fig. 2 is a partial elevational view showing the means for joining together the vertical support members of my invention;

Fig. 3 is a perspective view of an end portion of one of the rod members of my invention;

Fig. 4 is a side elevational view of another arrangement of the device of my invention shown in operative association with a bathtub;

Fig. 5 is a front elevational view of the device shown in Fig. 4; and

Fig. 6 is a perspective view showing the jointure means between the curved arm member and the support member.

A base member, generally indicated by numeral 8, comprises a pair of legs, each having downwardly extending legs 10 at the opposite extremities of a horizontally extending support member 12.

The free end of each of the legs 10 is provided with a rubber tip or cap 14.

The base member also includes a horizontally extending transverse member 16 which connects the member 12 in a manner best shown in Fig. 5. Reference to Fig. 1 will disclose that member 16 does not intersect the members 12 at the midpoints thereof but rather is joined thereto at a point on one side of the midpoint so that the member 16 is not disposed centrally of the base member, all for purposes presently to be observed.

A vertically disposed hollow sleeve member 20 is secured to the transverse member 16 at the midpoint thereof and extends therethrough so that portions thereof extend upwardly above and downwardly below member 16, all as is best shown in Fig. 4.

The upper extremity of member 20 is provided with a pair of outwardly extending ears 22 separated by a vertical slot 24 extending through the upper end of the member 20.

A screw member 26 extends transversely through aligned openings in which the ears 22 has threadedly engageable therewith a nut 28 which permits the drawing together of the ears so as to restrict the sleeve openings as will presently be observed.

A vertically disposed tubular lower support member 30 is slidably extendable through the sleeve member 20 and is manually movable relative thereto upon a loosening of the tightening means above described.

By tightening the screw and nut members 26 and 28, the member 30 may be held secure in any desired position relative to the base member as will be appreciated.

The lower free extremity of the member 30 is provided with a rubber cap device 32 for protective purposes.

A vertically disposed tubular upper support member 40 is telescopically receivable within the member 30 and is manually movable relative thereto by a loosening of a tightening device comprising a screw 36 and a nut 38 having similar characteristics and functions to the members 26 and 28 aforementioned.

The screw member 36 extends transversely through aligned openings in ears 62 like ears 22 shown by Fig. 2, on the upper end of the member 30. By tightening the members 36 and 38 relative to each other, the member 40 may be held secure in any desired position relative to the member 30. Thus, it will be appreciated that the over-all length or height of members 30 and 40 can be varied so as to obtain great or little height therewith all as may be desired.

A curved arm member is provided having a relatively long arm portion 52 and a relatively short arm portion 54. This member is telescopi-

cally receivable at either of its free extremities in the upper end of member 40.

A plurality of hanger rods 56 are provided in spaced relation along the portions 52 and 54 of the curved arm member and comprise rod like members which are slidably receivable through openings in the curved arm member so as to be disposed transversely relative thereto as shown in Fig. 5.

10 The rod members are slidably held relative to the curved arm member and the outer free extremities thereof are flattened as at 58 in Fig. 3 so as to lock the rod members relative to the curved arm members.

15 It will be appreciated that the long arm portion of the curved arm member may be inserted into the member 40 so as to provide a relatively vertically disposed hanger arrangement (as shown in Fig. 1) or the short arm portion may be inserted thereinto so as to provide a relatively horizontally disposed hanger arrangement (as shown in Figs. 4 and 5).

20 It will further be appreciated that if desired, the rod members 56 may be placed in a staggered relation relative to the curved arm member as shown in Fig. 1a so as to offer a greater area for the drying of clothes or the like hung thereon.

25 A plurality of hanger hooks 60 comprising U-shaped member are also provided. One side of each member 60 is provided with appropriately spaced openings 64 and the member 60 is receivable over a plurality of the rod members 56 thereby, all as is shown in Fig. 1. The member 60 is engaged with the particular rod members 56 before the turning out of the ends 58 of the rod members whereby the member 60 is held in operative engagement with the members 56.

30 The member 60 is slidable along and relative to the rod members 56 to any desired position as shown in Fig. 5 so that it may be positioned at any desired distance from the curved arm member.

35 The members 60 normally are provided in pairs, one on either side of the curved arm member, so that means is provided for the hanging therefrom of articles such as Venetian blinds or the like, the articles being suspended from the free side portion of the members 60 or from the transverse portion thereof as will be appreciated by reference to Figs. 4 and 1 respectively.

40 The upper extremity of the member 40 is provided with a pair of oppositely disposed notches 41 in the end of the tubular member as shown in Fig. 6. As aforesaid, either end of the curved arm member is insertable in the upper end of member 40 and the outermost rod member 56 at that end snugly nests in the notch 41 on either side of the portion 52 or 54 as the case may be thereby holding the curved arm member securely relative to the member 40.

45 As explained above, the transverse member 16 is not centrally disposed relative to the leg members but rather is offset at one side of a line intersecting the midpoints of the horizontally extending support members 12.

50 The device of the invention is adapted for insertion into a bathtub B as shown in Figs. 4 and 5 and depending on the width of the rim R of the tub B, the narrow width or the wide width of the base member may be used to embrace the rim of the tub. That is to say, it being appreciated that bathtubs of modern design are provided in a plurality of widths in the rims R, the 55 device of my design, in order to be adaptable to

all types and sizes must incorporate features which compensate for this variance. By providing a base member which is insertable over a narrow rim of a tub (such as shown in Fig. 4) or over a wide rim of a tub, I provide a device which accommodates the owners of all types of bathtubs.

The base member fits over the tub or chair arm or back, as desired, two of the legs 10 being slipped over and outside of the piece of furniture so as to embrace the outer wall thereof, and the member 30 is extended downwardly relative to the base member so as to rest upon the inner bottom area of the tub, or the floor in the case of a chair. Preferably, the member 30 is held snugly up against the side wall of the tub or chair.

The member 40 being pivotable relative to the member 30 is swung so that the curved arm member overlies or overhangs the tub whereby clothes or other articles upon drying will hang over the tub, all for obvious reasons.

The invention may be embodied in other specific forms without departing from the essential characteristics thereof. Hence, the present embodiments are therefore to be considered in all respects merely as being illustrative and not as being restrictive, the scope of the invention being indicated by the appended claims rather than by the foregoing description, and all modifications and variations as fall within the meaning and purview and range of equivalency of the appended claims are therefore intended to be embraced therein.

What it is desired to claim and secure by Letters Patent of the United States is:

1. A bathtub hanger comprising in combination, a support member, a base member having means for slidable adjustment upon and swingable relative to said support member, means fixed to said base member for engaging the rim of the bathtub and holding said support member in a vertical position in and relative to the bathtub, and an arm member carrying a plurality of hanger rods mounted for releasable engagement on said support member, said arm members being adapted for swinging movements to overlie the bathtub upon rotation of said support member relative to said base member.

2. A hanger construction adapted to be sup-

ported by the bottom and rim of a bathtub comprising in combination, a base having means for slidable adjustment and swinging of the support relative thereto, said base including an elongated horizontally disposed member having T-shaped members fixed on opposite ends thereof provided with horizontally disposed intermediate portions and spaced vertically and downwardly extending legs for resting on and engaging the rim of a bathtub and said support on the bottom of the bathtub, an arm member having angularly disposed arm portions, and the upper end of the support being adapted to telescopically and swingably receive an end of one of the said arm portions.

3. A hanger construction adapted to be supported by the bottom and rim of a bathtub comprising in combination, a base having spaced pairs of relatively spaced vertically disposed legs depending from opposite ends thereof for resting on and engaging the rim of a bathtub, an elongated support resting on the bottom of the bathtub, said base having means for vertical slidable adjustment and swinging of the support relative thereto, and an elongated arm member having angularly disposed arm portions carrying a plurality of outwardly extending hanger rods spaced longitudinally thereof, and the upper end of said support adapted to telescopically and swingably receive an arm portion of the arm member.

LEONARD MARTIN.
